MAGAZINE RACK OR THE LIKE

Dave Chapman, Chicago, and Kim Yamasaki, Lombard, Ill., assignors to Brunswick Corporation, Chicago, Ill., a corporation of Delaware

Filed Oct. 28, 1960, Ser. No. 62,655

Term of patent 14 years

(Cl. D33—2)

FIG. 1 is a front perspective view of a magazine rack or the like showing our new design;

FIG. 2 is a top plan view thereof;

FIG. 3 is a front elevational view thereof; and

FIG. 4 is a sectional view thereof, taken at about the line 4—4 of FIG. 3.

The dominant features of the design are shown in full lines in the drawing.

We claim:

The ornamental design for a magazine rack or the like, substantially as shown and described.
